UNITED STATES PATENT OFFICE

100,293

DESIGN FOR A CIRCULATING HEATER

Bradford Rymer, Cleveland, Tenn., assignor to
Dixie Foundry Company, Inc., Cleveland,
Tenn., a corporation of Tennessee

Application May 18, 1936, Serial No. 62,714

Term of patent 7 years

To all whom it may concern:

Be it known that I, Bradford Rymer, a citizen of the United States and a resident of Cleveland, in the county of Bradley and State of Tennessee, have invented a new, original, and ornamental Design for a Circulating Heater, of which the following is a specification, reference being had to the accompanying drawing, forming a part thereof.

In the drawing:

Figure 1 is a front perspective view of a circulating heater showing my new design.

Figure 2 is a rear perspective view of the same.

I claim:

The ornamental design for a circulating heater, as shown.

BRADFORD RYMER.
